CLAIM

The ornamental design for a stackable toiletry cabinet, as shown and described.

DESCRIPTION

FIG. 1 is a top, front, right side perspective view of the stackable toiletry cabinet of the present invention, with a door shown in an opened position;

FIG. 2 is a front elevational view of the stackable toiletry cabinet, with the doors shown in the closed position;

FIG. 3 is a rear elevational view of the stackable toiletry cabinet of FIG. 2;

FIG. 4 is a left side elevational view of the stackable toiletry cabinet of FIG. 2, the right view being a mirror image thereof;

FIG. 5 is a top plan view of the stackable toiletry cabinet of FIG. 2; and,

FIG. 6 is a bottom plan view of the stackable toiletry cabinet of FIG. 2.

The surfaces or portions of the article not shown in the drawing or described in the specification form no part of the claimed design.
